UNITED STATES PATENT OFFICE.

HARRY BAXTER, OF NEWMAN, ILLINOIS.

GRAIN-BUNDLE SHOCKER.

Application filed November 29, 1920. Serial No. 427,221.

To all whom it may concern:

Be it known that I, HARRY BAXTER, a citizen of the United States, residing at Newman, in the county of Douglas and State of Illinois, have invented a new and useful 5 Grain-Bundle Shocker, of which the following is a specification.

It is the object of my invention automatically to shock the bundles of grain 10 discharged from a binder.

My present invention is in large part a development and improvement of that set forth in my prior Patent No. 1,335,419, granted March 30, 1920; but is intended to 15 eliminate the manual labor required for the operation of the device shown in such prior patent, and thus make the formation of the shocks substantially wholly automatic.

The accompanying drawings illustrate my 20 invention: Fig. 1 is a perspective view of my improved automatic shocker, with parts of the associated binder and tractor; Fig. 2 is a diagrammatic view of the shock-former showing various positions which it has 25 in depositing a shock; Fig. 3 is a plan of the shocker; Fig. 4 is a side elevation of the shocker, taken from the binder side; Fig. 5 is a section on the line 5—5 of Fig. 4, showing a detail of the releasable lock of the 30 shock-former; Fig. 6 is a fragmentary horizontal section through the shock-former and associated parts, taken substantially on the axis of the shock-former; Fig. 7 is an enlarged detail of part of the shock-gripper 35 and its ratchet lock; Fig. 8 is a section on the line 8—8 of Fig. 10, showing in fragmentary side elevation the operating mechanism for the bundle-pusher or movable cylinder base; Fig. 9 is a plan of the front axle 40 of the shocker, and the driving parts associated therewith; Fig. 10 is a horizontal section on the line 10—10 of Fig. 8; Fig. 11 is a perspective view of the shock-former immediately after it has deposited a shock 45 on the ground; Fig. 12 is a diagrammatic view of a modified arrangement of the cylinder whereby the binder may discharge directly into the cylinder without an intermediate elevator; and Fig. 13 is a diagrammatic view of a modified form of the mounting of the front end of the cylinder, on a crank instead of on a roller operating on an inclined plane.

My improved shocker is arranged to 55 travel beside a binder 20, and may be drawn in common with the binder by a tractor 21,

only fragments of the binder and tractor being shown (Fig. 1) as they may be of any desired type. The shocker has a supporting frame 22 mounted on a front axle 60 23 and rear caster wheels 24, the front axle 25 being provided with supporting wheels 25 at least one of which preferably has ground-gripping projections 26 which insure turning of such wheel and of the axle 23, from 65 which the necessary power for operating the movable parts of the shocker is obtained. The frame 22 is connected to the tractor 21 by a chain 27 if the shocker is drawn by such tractor, and is properly spaced from 70 the binder 20 by a thrust bar 28.

Mounted on the frame 22 are a bundle-receiving cylinder 30 lying generally horizontal and having an axially slideable base 31 which constitutes a bundle-pusher, a 75 shock-former 32 comprising two hollow frusto-conical parts joined at their small ends and mounted to turn about a transverse axis so that either frustum may receive a group of bundles from the cylinder 80 by the operation of the cylinder base and may form such bundles into a proper shock shape and then rotate to deposit the formed shock on the ground, and in the preferred form of my invention an elevator 33 which 85 receives bundles or sheaves from the apron 34 of the binder 20 and raises such bundles and drops them into the cylinder through an opening 35 at the top of the latter. A guard 36 is provided for preventing the bundles 90 discharged from the upper end of the elevator 33 from overshooting the opening 35. If the cylinder 30 is sufficiently low and the apron 34 sufficiently high, the elevator 33 may be omitted and the apron 34 made to 95 discharge directly into the cylinder 30 through an upwardly oblique opening 35', as is indicated diagrammatically in Fig. 12; but generally it is desirable to provide the elevator 33. 100

The elevator 33, when provided, and the base or bundle-pusher 31 are both driven from the axle 23, but they are driven alternately so that only one of them operates at a time. For this purpose, the axle 23 has a 105 loose pulley 40 which is connected by a belt 41 to the upper roller 42 of the elevator 33, which pulley may be clutched to the axle 23 by a movable clutch member 43 operable by a shift lever 44; which shift lever is also 110 connected through a pin and slot 45 (Fig. 9) to a sliding yoke 46 connected to two sliding

clutch members 47 which when shifted in one direction clutch to the axle 23 two loosely mounted sprockets 48. The shift lever 44 is connected to the yoke 46 and to the clutch member 43 to operate them oppositely, to clutch the sprockets 48 to the shaft when the pulley 40 is unclutched, and vice versa.

The sprockets 48 are connected by chains 49 to sprockets 50 on two shafts 51 parallel to the axle 23 and in alignment with each other and spaced apart at their adjacent ends to permit the passage across the line of such aligned shafts of a push-rod 52 for the cylinder base or bundle-pusher 31. The push-rod 52 is provided with a series of cross pins 53 which project laterally therefrom on both sides so that they may cooperate with sprockets 54 carried by the adjacent ends 20 of the shafts 51; so that when the shafts 51 are rotated the sprockets 54 cooperate with the pins 53 first to drive the push-rod 52 and through it the bundle-pusher 31 rearward to push a group of bundles out of the cylinder 30, (the pins 53 then cooperating with the under sides of the sprockets 54,) and thereafter to move the push-rod and bundle-pusher forward to normal position, the pins 53 then cooperating with the upper 25 sides of the sprockets 54; as indicated in full and dotted lines in Fig. 8. The sprockets 54 cooperate with the end pins of the series of pins 53, when such end pins are reached, to swing the push-rod 52 from the under side to the upper side of the sprockets 54 and vice versa, the number of such pins being variable by removing or inserting one or more pins, as the condition of the grain being cut requires. The push-rod 52 is held 30 in cooperation with the sprocket wheels 54, on both the lower and upper sides, by suitable rollers 55.

The shift lever 44 is normally in the position (not shown) where it clutches the pulley 40 to the axle 23. It is moved to the other position when it is desired to deposit a shock in proper relation to the other shocks in the field, to unclutch the pulley 40 and stop the elevator and to clutch the sprockets 48 and produce a reciprocation of the bundle-pusher or cylinder base 31. The reverse clutch-shifting action is obtained automatically when such reciprocation is completed. For this purpose, the cylinder base 31 is provided with a forwardly projecting cam finger 60, which is stiffly flexible, and which when the cylinder base 31 is moved forward to complete its reciprocation strikes a pin 61 on the yoke 46 to shift such yoke and the shifting lever 44 to unclutch the sprockets 48 from the axle 23 and clutch the pulley 40 thereto, to start the elevator 33 into operation automatically when the reciprocation of the bundle-pusher is completed. The cam finger 60 is sufficiently stiff to operate the

yoke 46, but sufficiently flexible to bend when the shifting lever 44 is manually operated.

The rearward end of the pusher-rod 52 is pivotally mounted on a pin 65 in a carrying yoke 66 mounted on a slide pin 67 extending through the cylinder base 31, and a compression spring 68 is provided tending to push the yoke 66 away from such cylinder head. The pin 65 projects beyond the yoke 66 into guide slots in parallel guide plates 69 which guide the yoke 66 in its movements. This yielding connection permits the push-rod 52 to be moved to the desired extent necessary for its end pin at its free end to move upward around the sprockets 54 even though the cylinder head 31 is stopped before such end pin is reached, by reason of grain bundles of greater length, thus allowing for considerable variation in the length of the straw and in the distance to which the bundles are shoved into the cone frustums of the shock-former.

In addition, I preferably provide a tension spring 70 between the lower part of the cylinder base 31 and a point on the push-rod 52, tending to pull the free end of the push-rod downward and the entire rod toward the cylinder head 31. This permits the end pin 53 nearest such cylinder head 31 to pass around the sprockets 54 on the side away from such cylinder head when the latter reaches the forward limit of its movement even though such forward limit is reached somewhat before the push-rod 52 has moved forward sufficiently far to allow such end cross pin to pass such sprockets. In other words, the two springs 68 and 70 tend to hold the cross pin 65 at an intermediate point in the slots in the guide plates 69, so that there may be relative yielding between the push-rod and the cylinder head at both ends of their reciprocatory movement.

The cylinder head 31, as already stated, is slidable axially of the cylinder 30. To guide it in its movements, two forwardly projecting guide rods 75 are fixed to diametrically opposite points of such cylinder head and have a sliding fit within guides 76 fixed on the forward end of the cylinder 30. In addition, the cylinder head is provided with radially projecting guide bars 77 which extend through longitudinally extending guide slots 78 in the sides of the cylinder 30. These guide bars and guide slots also limit the relative movement between the cylinder head and cylinder; and the projecting guide bars 77 have in addition a releasing function for the holding device of the shock-former, as will be explained hereinafter.

Not only is the cylinder head 31 axially movable, but so is the cylinder 30 itself. In the preferred arrangement shown in Figs. 1, 3, and 4, the cylinder has a pair of supporting brackets 80 on each side, which

brackets are provided with rollers 81 which travel on two longitudinally extending side members 82 of the frame 22. These side members are provided with notches 83 in which the forward rollers 81 drop when the cylinder 30 is at the forward limit of its movement, so that such forward end is then lowered. The forward sides of these notches are vertical to serve as stops for the rollers, while the rearward sides are inclined so that when the cylinder 30 is pushed toward the rear the forward rollers will rise on the inclines to lift the forward end of the cylinder from its normally lower position to the same level as the rearward end. Thus in normal position the forward end of the cylinder is tilted downward, but when the cylinder is shoved rearward it is horizontal. This downward tilting of the forward end of the cylinder when in normal position tends to cause the bundles of grain to slide forward against the cylinder base 31 when they are dropped into the cylinder, with their butt ends against such cylinder head, thus producing an alinement of all such butt ends. The cylinder 30 is moved rearward by the friction of its inner surface with the grain bundles when the cylinder head 31 is pushed rearward, and is moved forward when the cylinder head 31 strikes the rear ends of the guides 76. If desired, guards 84 (shown only in Fig. 1) may be provided for limiting the upward movement of the forward rollers 81.

If desired, instead of having the forward rollers 81 drop into notches 83, the forward end of the cylinder 30 may be mounted on pivoted crank-arms 85, as indicated in Fig. 13, so that when the cylinder is shoved to the rear the forward end will be raised, in the same general way that it is raised by the travel of the forward rollers 81 upon the inclined rear sides of the notches 83.

The shock-former 32 normally lies in a horizontal position, with either end forward, to receive the bundles shoved out of the cylinder 30 by the bundle-pusher or cylinder base 31. This shock-former, which as stated comprises two hollow cone frustums joined at their small ends, is rotatably mounted on a transverse non-rotatable shaft 90 which extends through the center of the shock-former and is supported by its projecting ends. Each of these projecting ends is mounted for longitudinal sliding in a slideway 91, which is pivoted to the rear end of the main frame 22 on a pivot point 92 forward of the shaft 90, so that such slideway 91 and the shaft 90 may swing up and down. The downward swinging of each slideway is limited by a stop 93 which projects obliquely upward from the rear end of the frame 22 below the pivot point 92 and on which the slideway 91 normally rests. Each end of the shaft 90 is held from

turning in the slideway 91 by a pin 94 which extends through a suitable transverse hole in the shaft 90 and longitudinally through the center of the slideway, and is centered in such slideway by two compression springs 95 surrounding the pin 94 on each side of the shaft 90 and acting between the shaft and the respective ends of the slideway, as is perhaps most clear from Fig. 6. This pivotal mounting of the slideways 91 and the resilient mounting of the shaft 90 in such slideways permit the yielding of the shock-former both vertically and horizontally as conditions require, the vertical yielding by the swinging of the slideways 91 as the shock-former rotates to deposit a shock being diagrammatically indicated in Fig. 2, which shows five positions of the shock-former as it rotates through 180° during the forward travel of the shucker.

The shock-former 32 is normally held in horizontal position, with either end forward in position to receive bundles from the cylinder, by a pair of spring-pressed latches 100 suitably pivoted on the frame 22 and spring-pressed to latching position by springs 101, each of these latches 100 being provided with a hole through it for receiving a locking pin 102, of which there are two projecting oppositely laterally from each end of the shock-former 32. Each latch 100 is provided with a withdrawing finger 103 which projects upward past the outer edge of the corresponding side member 82 in position to be acted on by an inclined-plane cam 104 mounted on the outer side of a slide bar 105 resting on the top of said side member 82, said slide bar being spring-pressed downward against said side member by suitable leaf springs 106. The front end of each slide bar 105 is provided with a forwardly projecting hooked finger 107 having its hook directed downward and arranged to permit the corresponding guide bar 77 to pass beneath the hook (by lifting the finger 107 against the spring 106) when the cylinder base or bundle-pusher 31 finishes its rearward movement, and to grip such guide bar 77 and be pulled forward thereby when the cylinder base 31 starts forward. This forward movement of the hooked finger 107 carries the entire slide bar 105 with it, so that the cam 104 engages and pushes outward the releasing finger 103 to disengage the latch 100 from the pin 102 and permit the forward end of the shock-former 32, in which forward end there is now a formed shock ready to be deposited, to swing downward by the weight of the grain within it and deposit the formed shock on the ground in the manner clear from Figs. 2 and 11; after depositing the shock, the continued forward movement of the shucker causes the shock-former in being withdrawn from the deposited shock to continue its swinging to

the horizontal position, but with its ends reversed, in which position it is caught and latched by the action of the latches 100 on the pins 102 at the now forward end of the 5 shock-former. The forward movement of the slide bars 105 is stopped when it has released the latches 100. A shoulder 108 at the forward end of each slide bar strikes an inclined plane 109 provided on the side bar 82 10 and is lifted thereby to release the hooked finger 107 from the guide bar 77, whereupon a returning spring 99 attached to the rear end of the slide bar 105 returns the latter to its initial position.

15 In order to prevent the formed shock in the shock-former from dropping out prematurely as the shock-former rotates, I provide automatically acting shock-grippers within the cone frustums of the shock-former to hold the shock until the proper time to release it. These shock-grippers comprise sliding rods 110 mounted in laterally projecting slide bearings 111 on the sides of the cone frustums of the shock-former, 20 which rods 110 are spring-pressed outwardly by compression springs 112 and are provided at their inner ends with arc-shaped bows 113 lying in transverse slots 114 in the sides of the cone frustums. When the rods 110 are 25 pushed inward, the bows 113 compress the shock laterally and hold it within the cone. When the straw is short this gripping action may be supplemented by providing an arm 115 in connection with each bow 113, 30 such arm 115 having a pivotal mounting 116 within the cone frustum near its smaller end and being fastened to the bow 113 by a bolt 117 extending loosely through a hole in the arm 115 to permit the necessary movement 35 between the two; and on the outer end of each arm 115 is a supplemental bow 118 of a shape generally similar to that of the bow 113, for gripping the shock near the butt ends of the grain bundles. When the 40 straw is long, the arms 115 may be removed, by taking out the pins 116 and the bolts 117.

The bows 113, and the bows 118 if they are provided, are controlled by movements of the slide bars 105. Each rod 110 is provided at its outer end with a roller 120, which cooperates with a cam 121 on an arm 122 pivoted on the side member 82 substantially at the rear end of the latter, and the arm 122 is connected to the corresponding 50 slide bar 105 by a resiliently extensible link 123, formed of two relatively slidable parts spring-pressed to shorten the link length by a compression spring 124. When the slide bar 105 is pulled forward by the guide bar 55 77 when the cylinder base 31 starts forward, the arm 122 is swung (from full-line to dotted-line position in Fig. 6) to push the associated rod 110 inward to cause the bows 113 and 118 to grip the shock. The link 123 60 65 may stretch during this operation, as re-

quired by the size of the shock in the shock-former. When the bar 110 is pushed inward, it is held in the innermost position which it reaches, by a pawl 125 which cooperates with a number of latch notches 126 in the 70 side of such bar. The pawl 125 is spring-pressed to latching position by a spring 127, and is connected to a lever 128 provided with a roller 129 which cooperates with a cam 130. This cam is on the stationary shaft 90 and acts to withdraw the pawl 125 when the shock-former reaches vertical position, thus allowing the spring 112 to pull outward the 75 rod 110 and release the shock from the bows 113 and 118.

15 In operation, the binder 20 cuts and binds the grain and discharges the bound bundles onto the apron 34, whence the bundles are either discharged directly into the cylinder 30 through the opening 35' (Fig. 12) or are 80 picked up by the elevator 33 in the preferred form of my invention and dropped thereby through the opening 35 into the cylinder. While the bundles are being so fed to the cylinder, the latter and its base 85 31 are stationary in their forward position and the shock-former is horizontal, all as indicated in Fig. 1, and the front end of the cylinder is slightly dropped with relation to the rear end; and the clutches 43 and 47 90 are set to drive the roller 42 and not to drive the shafts 51. When it is desired to deposit a shock, as when a sufficient number of bundles are in the cylinder 30 and the desired point of deposit is reached, the shifting lever 44 is operated to set the clutches 47 and release the clutch 43, to stop the elevator 33 and start the reciprocation of the cylinder base 31. As the shafts 51 start to 95 rotate upon the setting of the clutches 47, they act through the sprockets 54 and push-rod 52 to push the cylinder head 31 toward the rear. The friction of the sheaves carries the cylinder 30 rearward also, until the rear arms 80 strike the forward end of the 100 shock-former 32, whereupon the cylinder stops and the continued rearward movement of the cylinder base 31 pushes the bundles out of the cylinder 30 and into the front cone frustum of the shock-former, head-end 105 first, and the conical shape of the shock-former compresses the head ends of the sheaves to make a conical shock. When the bundles are completely in the shock-former, the springs 95 and 68 may yield somewhat, 110 as required, to permit the end cross pin 53 to pass around the sprockets 54, after which the continued movement of such sprockets moves the cylinder head 31 forward, leaving the shock in the shock-former. As the 115 cylinder head 31 starts forward, the guide arms 77 slide the slide bars 105 forward, to release the latches 100 and cause clamping of the shock in the shock-former by the bows 113 and 118. The cylinder head 31 120 125 130

continues forward until it reaches its normal position, carrying the cylinder 30 with it; and when such normal position is reached the finger 60 strikes the pin 61 and 5 reverses the clutch setting to stop the shafts 51 and start again into operation the elevator 33. In the meantime, the weight of the sheaves in the forward end of the shock-former causes such forward end to swing 10 downward, so that the shock-former will pass through the cycle shown diagrammatically in Fig. 2, to deposit the shock on the ground and pass on therefrom as is indicated in Fig. 11. As the shock-former 15 passes through its cycle, and reaches the vertical position marked 3 in Fig. 2, the interaction of the rollers 129 with the cams 130 causes the pawls 125 to be withdrawn to permit the bows 113 and 118 to release the 20 shock.

This operation is repeated as often as desired, being initiated by the shifting lever 44, and stopping automatically when the depositing operation is completed.

25 I claim as my invention:

1. An automatic shocker, comprising the combination of a receptacle arranged to receive grain bundles from a binder, a shock-former for forming groups of bundles into 30 a shock and depositing the formed shock on the ground, and means for intermittently pushing the bundles from said receptacle into said shock-former.

35 2. An automatic shocker, comprising the combination of a receptacle arranged to receive grain bundles from a binder, a shock-former for forming groups of bundles into a shock and depositing the formed shock on the ground, means for intermittently pushing the bundles from said receptacle into 40 said shock-former, and means for stopping the feeding of bundles to said receptacle while the pushing means is operating.

45 3. An automatic shocker, comprising the combination of a receptacle arranged to receive grain bundles from a binder, a shock-former for forming groups of bundles into a shock and depositing the formed shock on the ground, means for intermittently pushing the bundles from said receptacle into 50 said shock-former, locking means for said shock-former for holding it in receiving position, and means controlled by said pushing means for releasing said locking means.

55 4. In a shocker, the combination of an elevator for receiving grain bundles from a binder, a receptacle into which said elevator discharges said grain bundles, discharging means for intermittently receiving from 60 said receptacle the grain bundles collected therein and depositing them in a shock on the ground, and means for driving said elevator and said discharging means alternately.

65 5. In a shocker, the combination of an

elevator for receiving grain bundles from a binder, a receptacle into which said elevator discharges said grain bundles, discharging means for intermittently receiving from said receptacle the grain bundles 70 collected therein and depositing them in a shock on the ground, driving mechanism for said elevator, driving mechanism for said discharging mechanism, and controlling mechanism for said two driving mechanisms 75 arranged to render one inoperative when the other is operative.

6. In a shocker, the combination of an elevator for receiving grain bundles from a binder, a receptacle into which said elevator discharges said grain bundles, discharging means for intermittently receiving from 80 said receptacle the grain bundles collected therein and depositing them in a shock on the ground, driving mechanism for said elevator, driving mechanism for said discharging mechanism, controlling mechanism for 85 said two driving mechanisms arranged to render one inoperative when the other is operative, and means for automatically operating said controlling mechanism to make the driving mechanism for the elevator operative upon the completion of an operation of said discharging mechanism.

7. In a shocker, the combination of a 90 cylinder arranged to receive grain bundles from a binder, a cylinder base reciprocable in said cylinder to push out the collected grain bundles therefrom, and a tapering shock-former arranged in position to receive 95 the grain bundles pushed out of said cylinder, said shock-former being movably mounted so that upon receiving the grain bundles from said cylinder it may swing about a transverse axis to deposit such bundles in 100 the form of a shock on the ground.

8. In a shocker, the combination of a cylinder arranged to receive grain bundles from a binder, a cylinder base reciprocable 110 in said cylinder to push out the collected grain bundles therefrom, a tapering shock-former arranged in position to receive the grain bundles pushed out of said cylinder, said shock-former being movably mounted so that upon receiving the grain bundles 115 from said cylinder it may swing about a transverse axis to deposit such bundles in the form of a shock on the ground, a lock for holding said shock-former in position to receive the grain bundles pushed out of said cylinder, and means for releasing said lock to permit the shock-former to swing when it has received a group of grain bundles from said cylinder.

9. In a shocker, the combination of a cylinder arranged to receive grain bundles from a binder, a cylinder base reciprocable in said cylinder to push out the collected grain bundles therefrom, a tapering shock-former arranged in position to receive the 125 130

grain bundles pushed out of said cylinder, said shock-former being movably mounted so that upon receiving the grain bundles from said cylinder it may swing about a transverse axis to deposit such bundles in the form of a shock on the ground, a lock for holding said shock-former in position to receive the grain bundles pushed out of said cylinder, and means controlled by the movement of said cylinder head for releasing said lock when said cylinder head reaches a predetermined point in its reciprocation.

10. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, and means for stopping the discharge of bundles into said cylinder during the reciprocation of said cylinder head.

11. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, and a reciprocable rod for operating said cylinder base, said rod being yieldingly connected to said cylinder base to permit variations in the movement of the latter.

12. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, and means for supporting said shock-former on such transverse axis to permit movement of the axis toward and from the cylinder as required by the number and length of the bundles pushed into it from the cylinder.

13. In a shocker, the combination of a cylinder arranged to receive grain bundles from a binder, a cylinder base reciprocable in said cylinder to push out the collected grain bundles therefrom, a tapering shock-

former arranged in position to receive the grain bundles pushed out of said cylinder, said shock-former being movably mounted so that upon receiving the grain bundles from said cylinder it may swing about a transverse axis to deposit such bundles in the form of a shock on the ground, a reciprocable rod for operating said cylinder base, said rod being yieldingly connected to said cylinder base to permit variations in the movement of the latter, and means for supporting said shock-former on such transverse axis to permit movement of the axis toward and from the cylinder as required by the number and length of the bundles pushed into it from the cylinder.

14. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, and means for supporting said shock-former on such transverse axis to permit movement of the axis as the shock-former swings to deposit a formed shock on the ground.

15. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, and means for supporting said shock-former on said transverse axis to permit vertical movement of the axis as the shock-former swings to deposit a formed shock on the ground.

16. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, and means for supporting said shock-former on

said transverse axis both to permit vertical movement of such axis as the shock-former swings to deposit a shock on the ground and to permit movement of the shock-former toward and from said cylinder as required by the length and number of the bundles pushed into it, and a reciprocable rod for operating said cylinder base, said rod being yieldingly connected to said cylinder base to permit variations in the movement of the latter.

17. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, and means for gripping the bundles in said shock-former to hold them in place as the shock-former swings toward depositing position.

18. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, means for gripping the bundles in said shock-former to hold them in place as the shock-former swings toward depositing position, and means for releasing said gripping means when the shock-former reaches depositing position.

45 19. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a transverse axis to deposit such bundles in the form of a shock on the ground, said cylinder being arranged to lie normally with its end remote from said shock-former lower than the other end, and means for causing said lower end to be raised when said cylinder base is moved to push out the grain bundles from the cylinder.

20. In a shocker, the combination of a cylinder arranged to receive grain bundles from a binder, a cylinder base reciprocable in

said cylinder to push out the collected grain bundles therefrom, and a tapering shock-former arranged in position to receive the grain bundles pushed out of said cylinder, said shock-former being movably mounted 70 so that upon receiving the grain bundles from said cylinder it may swing about a transverse axis to deposit such bundles in the form of a shock on the ground, said cylinder being arranged to lie normally with 75 its end remote from said shock-former lower than the other end.

21. In a shocker, the combination of a cylinder arranged to receive grain bundles from a binder, a cylinder base reciprocable in 80 said cylinder to push out the collected grain bundles therefrom, and a tapering shock-former arranged in position to receive the grain bundles pushed out of said cylinder, said shock-former being movably mounted 85 so that upon receiving the grain bundles from said cylinder it may swing about a transverse axis to deposit such bundles in the form of a shock on the ground, said cylinder being slidable toward and from the 90 shock-former by the reciprocation of said cylinder base.

22. In a shocker, the combination of a cylinder arranged to receive grain bundles from a binder, a cylinder base reciprocable 95 in said cylinder to push out the collected grain bundles therefrom, and a tapering shock-former arranged in position to receive the grain bundles pushed out of said cylinder, said shock-former being movably mounted 100 so that upon receiving the grain bundles from said cylinder it may swing about a transverse axis to deposit such bundles in the form of a shock on the ground, said cylinder being slidable toward and from the 105 shock-former by the reciprocation of said cylinder base, the mounting of said cylinder being arranged to raise the cylinder end remote from said shock-former relative to the other end when the cylinder is moved 110 toward the shock-former.

23. In a shocker, the combination of a cylinder arranged to receive grain bundles from a binder, a cylinder base reciprocable in said cylinder to push out the collected grain 115 bundles therefrom, and a tapering shock-former arranged in position to receive the grain bundles pushed out of said cylinder, said shock-former being movably mounted 120 so that upon receiving the grain bundles from said cylinder it may swing about a transverse axis to deposit such bundles in the form of a shock on the ground, said cylinder being slidable toward and from the shock-former by the reciprocation of said 125 cylinder base, the mounting of said cylinder being arranged to make the cylinder end remote from the shock-former lower than the other end when the cylinder is away from said shock-former and to raise such lower 130

end when the cylinder is moved toward the shock-former.

24. In a shocker, the combination of a hollow frusto-conical member arranged to receive grain bundles and form them into a shock and to swing on a transverse axis to deposit the formed shock on the ground, and means for supporting said shock-former on such transverse axis to permit movement 10 of such axis and shock-former longitudinally of the shocker.

25. In a shocker, the combination of a hollow frusto-conical member arranged to receive grain bundles and form them into a shock and to swing on a transverse axis to deposit the formed shock on the ground, and means for supporting said shock-former on 15 said transverse axis both to permit vertical movement of such axis as the shock-former swings to deposit a shock on the ground and to permit movement of the shock-former longitudinally of the shocker.

26. In a shocker, the combination of a hollow frusto-conical member arranged to receive grain bundles and form them into a shock and to swing on a transverse axis to deposit the formed shock on the ground, and hinged members swingable up and down and in which said shock-former is resiliently pivotally mounted on said transverse 30 axis.

27. In a shocker, the combination of a hollow frusto-conical member arranged to receive grain bundles and form them into a shock, hinged members swingable up and down, and means for mounting said shock-former in said hinged members to permit rotation and longitudinal translation of said shock-former relative to said swinging members.

28. In a shocker, the combination of a hollow frusto-conical member arranged to receive grain bundles and form them into a shock and to swing on a transverse axis to deposit the formed shock on the ground, and 45 means for gripping the bundles in said shock-former to hold them in place as the shock-former swings toward depositing position.

29. In a shocker, the combination of a hollow frusto-conical member arranged to receive grain bundles and form them into a shock and to swing on a transverse axis to deposit the formed shock on the ground, means for gripping the bundles in said 50 shock-former to hold them in place as the shock-former swings toward depositing position, and means for releasing said gripping means when the shock-former reaches 55 depositing position.

30. In a shocker, the combination of a cylinder arranged to receive grain bundles from a binder, a cylinder base reciprocable in said cylinder to push out the collected grain bundles therefrom, a tapering shock-former arranged in position to receive the grain bundles pushed out of said cylinder, said shock-former being movably mounted so that upon receiving the grain bundles from said cylinder it may swing about a 60 transverse axis to deposit such bundles in the form of a shock on the ground, and means operable upon reciprocating the cylinder base for lifting the end of the cylinder remote from the shock-former.

In witness whereof, I have hereunto set my hand at Indianapolis, Indiana, this 26th day of November, A. D. one thousand nine hundred and twenty.

HARRY BAXTER.
